PORTABLE DISPLAY RACK FOR OIL CANS

Robert R. Hellmann, Stroudsburg, Pa.

Application May 8, 1957, Serial No. 46,064

Term of patent 3½ years

(Cl. D80—10)

FIG. 1.

FIG. 2.

Figure 1 is a front perspective view of the portable display rack for oil cans embodying my new design; and Fig. 2 is a rear perspective view.

I claim:

The ornamental design for a portable display rack for oil cans, substantially as shown.
